UNITED STATES PATENT OFFICE.

WILLIAM HOLLINGSWORTH, OF BALTIMORE, MARYLAND.

CONVEYER.

Application filed February 19, 1926. Serial No. 89,469.

This invention relates to a conveyer designed primarily for use in connection with bronzing machines. It has been the practice heretofore to interpose a stationary conveyer structure between a printing press and a bronzing machine so that as each sheet is printed it will be carried automatically to the bronzing machine. It frequently happens, however, that the printing press to which the conveyer is connected is not in use and that sheets printed on some other press are to be fed into the bronzer. As the conveyer is fixedly connected to both machines it is necessary for the helper who supplies the bundles of sheets that are to be fed into the bronzer, to place the bundles on the table of the machine from one side thereof. This, however, has interfered with the work of the operator or feeder standing at the side of the bronzing machine. Consequently there has been a considerable loss of time and consequent increase in cost of bronzing.

It is an object of the present invention to provide a shiftable conveyer for installation between a printing press and a bronzing machine, simple and efficient means being employed whereby this conveyer can be elevated out of normal position when not in use, enabling the operator who is feeding the sheets to the bronzer to remain continuously at his post while the bundles of sheets are being arranged on the table from the back and not from the side as heretofore.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a side elevation of the conveyer, a portion thereof being broken away and the same being shown in position on a printing press and a bronzing machine parts of which are shown in elevation.

Figure 2 is a side elevation showing the conveyer elevated out of normal position, portions of the conveyer being broken away.

Figure 3 is a plan view of the conveyer.

Figure 4 is a front elevation of a portion of the elevating mechanism.

Referring to the figures by characters of reference A designates a portion of a bronzing machine provided with the usual table B on which the sheets to be bronzed are placed in piles if they are to be fed by hand. A platform C is located at one side of the bronzer and the person who feeds the sheets into the machine stands on this platform.

A portion of a printing press has been indicated at D. As heretofore stated it has been the practice to mount a conveyer fixedly on the printing press and on the table of the bronzing machine so that the sheets, when printed, will be conveyed to the bronzing machine. In the present instance the conveyer is of special construction so that it can be elevated out of normal position when not in use, thereby giving access to the back of the table B where an attendant can place the bundles of paper without the necessity of standing on the platform C and interfering with the work of the person feeding the machine. This conveyer is made up of three sections, namely, a main section 1, an intermediate section 2 and an end section 3. Sections 1 and 2 are hingedly connected by means of a transverse shaft 4 and the free end of the main section 1 is adapted to be mounted on a portion of a printing press B as shown at 5 in Figure 1. A roll 6 is carried by the main section 1 and a pair of rolls indicated at 7 and 8 is carried by the intermediate section 2 at points close to the shaft 4. These rolls 7 and 8 have shafts 9 and 10 respectively projecting at one end into a housing 11 carried by one side portion of the intermediate section 2. A sprocket or a pulley indicated generally at 12 is arranged within the housing 11 and secured to the shaft 9 while another sprocket or pulley indicated at 13 is secured to one end of the shaft 10 and is arranged within the housing 11. These two sprockets or pulleys are connected by an endless chain or belt 14 whereby the two rolls 7 and 8 are caused to rotate simultaneously in the same direction.

Endless belts 15 are mounted on the roll 6 and the upper flights of these belts extend over the shafts 4. The belts engage the roll 7 and the lower flights thereof extend under the shaft 4. Roll 7 has a pulley 7' or the like for receiving motion from a belt or other suitable means, not shown. Thus it

- will be seen that when the two sections 1 and 2 of the conveyer are in use as shown in Figure 1 the belts 15 will be driven by the rolls 7 and will operate to convey sheets 5 from the press longitudinally of the section 1. The section 3 of the conveyer is hingedly connected to the intermediate section 2 as shown at 16 and is provided at its free end with bearing blocks 17 in which is journaled 10 a roll 18. A transverse tie rod 19 connects the sides of the section 3 close to the roll 18. Endless belts 20 are mounted on the rolls 18 and 8 and the lower flights of these belts extend under a transverse rod 21 which connects the sides of the intermediate frame 2 between the roll 8 and the hinge connections 16. Another rod 22 connects the bearings 17 and has fingers 23 pivotally connected thereto and normally suspended therefrom. 15 The roll 18 is interposed between the rods 19 and 22 as shown in Figure 3.
- The sides of the intermediate section 2 of the conveyer are hingedly connected to ears 24 upstanding from side strips 25 which are 20 fastened to the sides of the table B of the bronzing machine A. Studs 26 are extended laterally from the sides of the intermediate section 2 where connected to the ears 24 and these studs are provided with heads 27 as 25 shown particularly in Figure 3. Braces 28 are pivotally connected to the end section 3 adjacent the centers of the sides thereof and the free ends of these braces are forked as at 29. Thus when the section 3 is swung upwardly relative to the section 2 it becomes possible to place the forked ends 29 of the braces astride the studs 26 where they will be retained against lateral displacement by the heads of the studs.
- 30 Pivottally mounted on the rod 21 close to the sides of the section 2 are arcuate racks 30 meshing with gears 31 secured to a transverse shaft 32 journaled in bearings 33 carried by the strips 25. A longitudinal groove 34 is formed in the convex face of each rack 30 and projecting into each of these grooves is a lug 35 extending from a guide block 36 extending laterally from the adjacent strip 25.
- 35 A hand wheel 37 is secured to the shaft 32 and constitutes a means whereby the shaft and its gears 31 can be rotated to raise or lower the racks 30. For the purpose of supporting the racks in raised positions, pins 38 are insertable through openings in the racks so as to bear downwardly on the strips 25. These pins can be connected to said strips by chains 39 or other suitable means.
- 40 Under normal conditions the conveyer is arranged as shown in Figure 1 with the sections 1, 2 and 3 substantially in alinement. One end portion of the section 1 bears downwardly on a portion of the printing press D while the end section 3 rests

upon the table B of the bronzing machine. When thus located the fingers 23 project into the feed opening of the bronzing machine. As before stated the roll 7 is adapted to be driven by any suitable mechanism not shown. Thus as the printed sheets are delivered from the press they will travel with the endless belts 15 and be transferred from these belts to the belts 20 which, in turn, will direct the sheets along the fingers 23 into the bronzing machine.

Should it be desired to feed into the bronzing machine sheets that have been printed on some other press, a hoist of any preferred construction and which has been indicated generally at H in Figure 2 is connected to the section 1 of the conveyer preferably at a point adjacent the press D. This hoist is then used for lifting one end portion of the section E so as to support it at a desired distance above its normal position. Shaft 32 is rotated by means of the hand wheel 37 and the gears 31 will cause the racks 30 to move upwardly after which the pins 38 can be inserted into the rack so as to hold them in raised position. This upward movement of the rack will cause the intermediate section 2 to swing upwardly to the position shown in Figure 2 so that the section 1 will thus be supported in a substantially horizontal position away from the table B of the bronzing machine. The short end section 3 is then swung upwardly by hand or in any other manner desired until the braces 28 can be placed with their forked ends astride the studs 26. Consequently section 3 can be supported in an upwardly inclined position as shown in Figure 2. After the parts have thus been adjusted the operator engaged in feeding sheets to the bronzing machine takes his position on the platform C after which the stacks of paper can be placed on the table B. This can be done without disturbing the person on the platform C because it is possible for the assistant who is arranging the bundles to stand at the back of the table and properly position the bundles thereon. As heretofore explained it has been necessary heretofore to place these bundles on the table B from the side and this could only be done by interrupting the work of the person feeding the sheets to the machine. By mounting the conveyer as described, however, the feeding operation can continue uninterrupted and a considerable saving of time will result.

It will be noted that when the conveyer is elevated as shown in Figure 2 the slack in the belts 15 resulting from the relative movement of the sections 1 and 2 will be taken up by the shaft 4 which will come against and support the upper flights of the belts. At the same time the slack in the belts 20 will be taken up by the rod 21 which will engage the lower flights of the

belts 20 as shown in Figure 2. Danger of the belts becoming displaced during the raising and lowering of the elevator is thus reduced to the minimum.

5 Although the ends of the braces 28 have been shown and described as forked, it is to be understood that, under some conditions they can be slotted instead.

10 In the structure shown the sections of the conveyer are supported substantially in alinement when in use. This is not essential, however. When some types of presses are used with the bronzer the sections can be maintained out of alinement while in use.

15 What is claimed is:

1. The combination with a supporting structure, of a conveyer including an intermediate section hingedly connected to said structure, a main section hingedly connected 20 to one end portion of the intermediate section, an end section hingedly connected to the intermediate section at a point between the ends of said intermediate section, a conveying belt carried by the main and intermediate sections, a conveying belt carried by the end and intermediate sections, said belts being movable in the same direction simultaneously, cooperating means upon the end and intermediate sections for supporting the end section at an angle to the intermediate section, and cooperating means upon the intermediate section and the supporting structure for adjusting the intermediate section angularly, thereby to elevate one end 30 of the end section and of the main section relative to the supporting structure.

2. A conveyer including a main section, an end section, an intermediate section hinged at one end to the main section and 40 at its other end to a support, said intermediate section being hingedly connected between its ends to one end of the end section, endless conveying belts carried by the end and intermediate sections, endless conveying belts carried by the main and intermediate sections, all of said belts being movable in the same direction, and means for 45 swinging the intermediate section about its point of connection with its support, thereby 50 to elevate simultaneously those end portions of the end and main sections connected to the intermediate section.

3. A conveyer including a main section, an end section, an intermediate section hinged at one end to the main section and 55 its other end to a support, said intermediate section being hingedly connected between its ends to one end of the end section, endless conveying belts carried by the end and intermediate sections, endless conveying belts carried by the main and intermediate sections, all of said belts being movable in the same direction, means for swinging the intermediate section about its point of connection with its support, thereby to elevate those 60 end portions of the end and main sections connected to the intermediate section, said end section being adjustable angularly about its point of connection with the intermediate section, cooperating means upon the end 65 and intermediate sections for holding the end section against downward movement relative to the intermediate section, and an adjustable support for the free end portion of the main section. 75

4. The combination with a bronzing machine having a feed table and a platform at one side thereof, of a conveyer including an intermediate section hingedly connected to the table and normally resting thereon and 80 extending beyond the end thereof, a main section hingedly connected to one end of the intermediate section and normally extended beyond the table, an end section hingedly connected to the intermediate section at a 85 point between the ends thereof and normally resting on the table, cooperating means upon the intermediate section and table for elevating said intermediate section relative to the end portion of the table, thereby to 90 simultaneously elevate those ends of the main and end sections connected to the intermediate section, cooperating means upon the end section and the intermediate section for holding said end section with its free end 95 elevated above the table while the intermediate section is in elevated position, and adjustable means for supporting the free end of the main section above the plane of the table and beyond the end thereof. 100

In testimony that I claim the foregoing as my own, I have hereto affixed my signature.

WILLIAM HOLLINGSWORTH.
